*FIG. 1**FIG. 2**FIG. 3**FIG. 4***APPARATUS AND METHOD FOR
NITRIDING GRAIN-ORIENTED
ELECTRICAL STEEL SHEET**

TECHNICAL FIELD

The disclosure relates to an apparatus and a method that are suitable for nitriding a grain-oriented electrical steel sheet.

BACKGROUND

A grain oriented electrical steel sheet is a soft magnetic material used as an iron core material of transformers and generators, and is required to have excellent magnetic properties, in particular low iron loss. This steel sheet has a texture in which the <001> direction, which is an easy magnetization axis of iron, is highly accorded with the rolling direction of the steel sheet. Such texture is formed through the so-called secondary recrystallization where crystal grains with (110)[001] orientation referred to as Goss orientation are preferentially grown massively, during secondary recrystallization annealing in the production process of the grain-oriented electrical steel sheet.

Conventionally, such grain-oriented electrical steel sheets have been manufactured by heating a slab containing 4.5 mass % or less of Si and inhibitor components such as MnS, MnSe and AlN to 1300°C or higher, thereby dissolving the inhibitor components, then subjecting the slab to hot rolling to obtain a hot rolled steel sheet, and then subjecting the hot rolled steel sheet to hot band annealing as necessary, and subsequent cold rolling once, or twice or more with intermediate annealing performed therebetween until reaching final sheet thickness, then subjecting the steel sheet to primary recrystallization annealing in wet hydrogen atmosphere to perform primary recrystallization and decarburization, and then applying thereon an annealing separator mainly composed of magnesia (MgO) and performing final annealing at 1200°C for around 5 hours for secondary recrystallization and purification of inhibitor components (e.g. see U.S. Pat. No. 1,965,559A (PTL 1), JPS4015644B (PTL 2) and JPS5113469B (PTL 3)).

However, high temperature heating of a slab not only causes an increase in apparatus costs to achieve heating, but also increases the amount of scale generated during hot rolling and decreases production yield, and further, it causes problems including complicated maintenance of facilities, and therefore, recent demands for reduction in production costs could not be met.

For this reason, various developments have been made for a technique of causing secondary recrystallization without containing inhibitor components in the slab. For example, a technique capable of stably causing secondary recrystallization without containing inhibitor components in the slab, by increasing S content in the steel matrix after primary recrystallization annealing and before completion of secondary recrystallization (sulfur increasing method) has been proposed (JP4321120B (PTL 4)).

Further, a technique that enables strengthening inhibitors after primary recrystallization annealing and before completion of secondary recrystallization and stably causing secondary recrystallization without containing inhibitor components in the slab, by performing gas nitriding before or after decarburization annealing (JP2771634B (PTL 5)), as well as a technique of disposing a reducing zone in front of

a nitriding zone to provide a reducing effect to the oxide layer of the steel sheet surface (JP03122227A (PTL 6)) have been proposed.

Further, in order to perform uniform nitriding over the whole strip during such gas nitriding process, a method of dividing and adjusting the nitriding gas supplied by a nozzle or a spray at the center part of the steel sheet and both ends of the steel sheet, has been proposed (JP3940205B (PTL 7)).

 PTL 6: JPH03122227A
 20 PTL 7: JP3940205B

SUMMARY

However, with the technique disclosed in PTL 4, there 25 were cases where the non-uniformity in the temperature and atmosphere during coil heating caused variation in the increase amount of sulfur in the coil and differences in secondary recrystallization behavior, which lead to variation of magnetic properties.

30 Further, the techniques disclosed in PTLs 5 to 7 are methods of performing nitriding by spraying nitriding gas on the steel sheet. Therefore, non-uniformity of the furnace temperature in terms of duration and position, and difference in decomposition amount of nitriding gas in pipes caused by 35 heat could cause a difference in nitrogen increase depending on the area of the strip, and as a result, secondary recrystallization could become non-uniform and lead to deterioration of magnetic properties.

It could therefore be helpful to provide an apparatus for 40 nitriding a grain-oriented electrical steel sheet which is very useful in obtaining excellent magnetic properties with no variation without containing inhibitor components in the slab when producing a grain-oriented electrical steel sheet, by performing appropriate nitriding before secondary recrystallization and uniformly dispersing inhibitor forming elements over the full length and full width of the strip, together with a nitriding method using the nitriding apparatus.

In order to solve the above problems, we have made 50 intensive studies.

As a result, we discovered that, when performing continuous nitriding of a strip (steel sheet), by performing nitriding by utilizing glow discharge, the amount of nitridation can be controlled with high accuracy, the variation of 55 said amount can be eliminated, the time required for treatment can be reduced, and therefore excellent magnetic properties can be obtained stably for the whole strip.

Further, we discovered that the above described plasma nitriding by glow discharge is the optimal structure as an 60 apparatus required for nitriding the strip, and completed the disclosure.

We thus provide:

1. An apparatus for nitriding a grain-oriented electrical steel sheet for continuously nitriding a strip continuously being fed after cold rolling and before secondary recrystallization annealing in a production line of a grain-oriented electrical steel sheet, comprising:

a nitriding zone for nitriding the strip;
a cooling zone for cooling the strip; and
an optional heating zone provided upstream of the nitrid-

ing zone for heating the strip, wherein,
the nitriding zone is provided with glow discharge
electrodes, and

the strip is subjected to plasma nitriding by glow
discharge with the glow discharge electrodes function-
ing as positive electrodes and the strip function-
ing as a negative electrode.

2. The apparatus for nitriding a grain-oriented electrical
steel sheet according to aspect 1, wherein the nitriding zone
is kept under reduced pressure.

3. The apparatus for nitriding a grain-oriented electrical
steel sheet according to aspect 2, wherein at least one of the
heating zone and the cooling zone is kept at a state with a
lower degree of pressure reduction compared to the nitriding
zone and reduced pressure compared to atmospheric pres-
sure.

4. The apparatus for nitriding a grain-oriented electrical
steel sheet according to any of aspects 1 to 3, further
comprising an upstream atmosphere adjusting zone pro-
vided between the heating zone and the nitriding zone, and
a downstream atmosphere adjusting zone provided between
the nitriding zone and the cooling zone.

5. The apparatus for nitriding a grain-oriented electrical
steel sheet according to aspect 4, wherein the upstream
atmosphere adjusting zone and the downstream atmosphere
adjusting zone are each divided into multiple air chambers
where the degrees of pressure reduction are individually
adjustable.

6. The apparatus for nitriding a grain-oriented electrical
steel sheet according to aspect 5, wherein the degrees of
pressure reduction of the air chambers in the upstream
atmosphere adjusting zone are gradually increased toward
the nitriding zone, while the degree of pressure reduction of
the air chambers in the downstream atmosphere adjusting
zone are gradually decreased toward the cooling zone.

7. The apparatus for nitriding a grain-oriented electrical
steel sheet according to any of aspects 1 to 6, wherein the
inside of the nitriding zone is divided into multiple zones in
the width direction of the strip to allow individual controls
of nitriding inside each divided zone.

8. A method for nitriding a grain-oriented electrical steel
sheet comprising plasma nitriding the strip by glow dis-
charge using the apparatus according to any of aspects 1 to
7 after cold rolling and before secondary recrystallization
annealing during producing a grain-oriented electrical steel
sheet.

With this disclosure, it is possible to suppress variation of
nitriding and to stably guarantee a uniform amount of
nitridation for the whole strip, and therefore it is possible to
stably obtain excellent magnetic properties over the full
length and full width of the strip.

Further, with this method, nitrogen gas can be used as a
nitrogen source, and therefore nitrogen sources which may
cause environmental problems such as ammonia required for
performing gas nitriding, cyan salt required for performing
salt bath nitriding or the like do not have to be used. For
these reasons, our method has a significant industrial use-
fulness.

BRIEF DESCRIPTION OF THE DRAWINGS

In the accompanying drawings:

FIG. 1 schematically shows a preferable example of the
nitriding apparatus of the disclosure.

FIG. 2 shows a preferable example of a plasma nitriding
device according to the disclosure.

FIG. 3 shows another example of a plasma nitriding
device according to the disclosure.

FIG. 4 schematically shows another example of the nitrid-
ing apparatus of the disclosure.

DETAILED DESCRIPTION

10. Our methods and components will be described in detail
below.

FIG. 1 schematically shows a preferable example of the
nitriding apparatus of the disclosure. In the figure, a heating
zone is labeled 1, a nitriding zone is labeled 2, and a cooling
zone is labeled 3. Further, a strip (steel sheet) continuously
passing inside the nitriding apparatus with a structure com-
prising the aforementioned components is labeled 4. The
heating zone may be provided when required and is not
always necessary.

20. In the disclosure, a strip 4 is subjected to plasma nitriding
by glow discharge in the above nitriding zone 2.

FIG. 2 shows a preferable example of a plasma nitriding
device according to the disclosure. In the figure, glow
discharge electrodes are labeled 5, pinch rolls which also
25 serve as electrode rolls are labeled 6, and in this example,
glow discharge electrodes 5 are disposed above and below
the strip 4. The inside of the nitriding zone 2 is filled with
nitrogen gas and hydrogen gas as nitrogen sources.

With the glow discharge electrodes 5 functioning as
30 positive electrodes and the strip 4 functioning as a negative
electrode, voltage is applied between the electrodes via
pinch rolls (electrode rolls) to generate glow discharge on
both sides of the strip 4, to subject both sides of the strip 4
to nitriding at the same time in plasma atmosphere.

35. Further, FIG. 3 shows another example of a plasma
nitriding device according to the disclosure. In this example,
glow discharge is generated with a strip 4 arranged to be
along electrode rolls 6 disposed opposite to positive elec-
40 trodes (glow discharge electrodes) 5. In this example, nitrid-
ing is performed on only one side of the strip 4. Therefore,
in order to perform nitriding on both sides of the strip 4,
another nitriding device will be required.

When performing the above nitriding, the strip is prefer-
ably heated to a temperature of 400° C. or higher.

45. Further, the inside of the nitriding zone is preferably kept
under a reduced pressure.

Further, although the heating zone and the cooling zone
have a lower degree of pressure reduction compared to the
nitriding zone, it is preferable for them to be kept in a state
with reduced pressure compared to atmospheric pressure,
and by doing so, heat exchange due to convection tends to
proceed, and heating and cooling efficiency can be
improved.

50. The inside of the nitriding zone is preferably depressur-
ized to around 0.5 torr to 10 torr which is a preferable glow
discharge condition, and the heating zone and the cooling
zone are preferably depressurized, with a lower degree of
pressure reduction, to around 30 torr to 500 torr.

55. Next, FIG. 4 shows an upstream atmosphere adjusting
zone 7-1 and a downstream atmosphere adjusting zone 7-2
with a nitriding zone 2 in between.

In this case, each of the upstream atmosphere adjusting
zone 7-1 and the downstream atmosphere adjusting zone 7-2
is preferably divided into multiple air chambers where the
60 degrees of pressure reduction are individually adjustable. In
a preferable construction, the degrees of pressure reduction
of the air chambers in the upstream atmosphere adjusting

5

zone 7-1 are gradually increased toward the nitriding zone 2, while the degree of pressure reduction of the air chambers in the downstream atmosphere adjusting zone 7-2 are gradually decreased from the nitriding zone 2 toward the cooling zone 3.

As the seal between each zone and each air chamber, conventionally known airtight seals may be used, such as rolls, seal pads and the like.

In a preferable structure, the inside of the nitriding zone is divided into multiple zones in the width direction of the strip where nitriding can be performed individually inside each divided zone. By adopting such structure, it is possible to effectively eliminate non-uniformity in nitridation in the width direction of the strip, such as excessive nitriding of the edges due to edge effects.

The heating zone can be omitted if it is disposed in a continuous line for performing other necessary treatment and the strip is already heated, or if the heating by plasma irradiation at the time of plasma nitriding is sufficient.

Further, in a case where another treatment is performed after plasma nitriding with the strip at a heated state, the cooling zone may be disposed after the zone for such treatment.

Further, the nitriding apparatus disclosed herein may be an independent apparatus that continuously performs only nitriding, or be attached to a processing line for performing another treatment, and in the case of a continuous line, it may be attached to the optimal place considering conditions including efficiency.

In the disclosure, the strip which is the material to be treated is not particularly limited and, as long as it is a grain-oriented electrical steel strip, any conventionally known strip is applicable.

REFERENCE SIGNS LIST

- 1 Heating Zone
- 2 Nitriding Zone
- 3 Cooling Zone
- 4 Strip (Steel Sheet)
- 5 Glow Discharge Electrode
- 6 Pinch Roll (also serving as Electrode Roll)
- 6' Electrode Roll

The invention claimed is:

1. An apparatus for nitriding a grain-oriented electrical steel sheet, comprising:
  - a nitriding zone for continuously nitriding a strip in a feeding direction;
  - a cooling zone for cooling the strip; and
  - an optional heating zone provided upstream of the nitriding zone for heating the strip, wherein,
    - the nitriding zone is provided with glow discharge electrodes,
    - the strip is subjected to plasma nitriding by glow discharge with the glow discharge electrodes functioning as positive electrodes and the strip functioning as a negative electrode, and
    - the inside of the nitriding zone is divided into multiple zones in a width direction of the strip to allow individual controls of nitriding inside each divided zone.
2. The apparatus for nitriding a grain-oriented electrical steel sheet according to claim 1, wherein the nitriding zone is kept under reduced pressure.

6

3. The apparatus for nitriding a grain-oriented electrical steel sheet according to claim 2, wherein at least one of the heating zone and the cooling zone is kept at a state with a lower degree of pressure reduction compared to the nitriding zone and reduced pressure compared to atmospheric pressure.

4. The apparatus for nitriding a grain-oriented electrical steel sheet according to claim 1, further comprising an upstream atmosphere adjusting zone provided between the heating zone and the nitriding zone, and a downstream atmosphere adjusting zone provided between the nitriding zone and the cooling zone.

5. The apparatus for nitriding a grain-oriented electrical steel sheet according to claim 4, wherein the upstream atmosphere adjusting zone and the downstream atmosphere adjusting zone are each divided into multiple air chambers where the degrees of pressure reduction are individually adjustable.

6. The apparatus for nitriding a grain-oriented electrical steel sheet according to claim 5, wherein the degrees of pressure reduction of the air chambers in the upstream atmosphere adjusting zone are gradually increased toward the nitriding zone, while the degree of pressure reduction of the air chambers in the downstream atmosphere adjusting zone are gradually decreased toward the cooling zone.

7. A method for nitriding a grain-oriented electrical steel sheet comprising plasma nitriding the strip by glow discharge using the apparatus according to claim 1 after cold rolling and before secondary recrystallization annealing during producing a grain-oriented electrical steel sheet.

8. The apparatus for nitriding a grain-oriented electrical steel sheet according to claim 2, further comprising an upstream atmosphere adjusting zone provided between the heating zone and the nitriding zone, and a downstream atmosphere adjusting zone provided between the nitriding zone and the cooling zone.

9. The apparatus for nitriding a grain-oriented electrical steel sheet according to claim 8, wherein the upstream atmosphere adjusting zone and the downstream atmosphere adjusting zone are each divided into multiple air chambers where the degrees of pressure reduction are individually adjustable.

10. The apparatus for nitriding a grain-oriented electrical steel sheet according to claim 9, wherein the degrees of pressure reduction of the air chambers in the upstream atmosphere adjusting zone are gradually increased toward the nitriding zone, while the degree of pressure reduction of the air chambers in the downstream atmosphere adjusting zone are gradually decreased toward the cooling zone.

11. The apparatus for nitriding a grain-oriented electrical steel sheet according to claim 3, further comprising an upstream atmosphere adjusting zone provided between the heating zone and the nitriding zone, and a downstream atmosphere adjusting zone provided between the nitriding zone and the cooling zone.

12. The apparatus for nitriding a grain-oriented electrical steel sheet according to claim 11, wherein the upstream atmosphere adjusting zone and the downstream atmosphere adjusting zone are each divided into multiple air chambers where the degrees of pressure reduction are individually adjustable.

13. The apparatus for nitriding a grain-oriented electrical steel sheet according to claim 12, wherein the degrees of pressure reduction of the air chambers in the upstream atmosphere adjusting zone are gradually increased toward the nitriding zone, while the degree of pressure reduction of

the air chambers in the downstream atmosphere adjusting zone are gradually decreased toward the cooling zone.
